US00D773543S

(12) **United States Design Patent** (10) **Patent No.:** **US D773,543 S**
Fan et al. (45) **Date of Patent:** **** Dec. 6, 2016**

(54) **VACUUM SEALER**

(71) Applicants: **Eric Fan**, San Leandro, CA (US); **Xiao Zheng Yang**, San Leandro, CA (US); **Gilbert Milam**, San Leandro, CA (US)

(72) Inventors: **Eric Fan**, San Leandro, CA (US); **Xiao Zheng Yang**, San Leandro, CA (US); **Gilbert Milam**, San Leandro, CA (US)

(**) Term: **15 Years**

(21) Appl. No.: **29/534,000**

(22) Filed: **Jul. 24, 2015**

(51) LOC (10) Cl. **15-09**

(52) U.S. Cl. USPC **D15/146**

(58) **Field of Classification Search**

USPC D15/145, 146
 See application file for complete search history.

Primary Examiner — Patricia Palasik(74) *Attorney, Agent, or Firm* — Larry D. Johnson(57) **CLAIM**

The ornamental design for a vacuum sealer, as shown.

DESCRIPTION

FIG. 1 is a front perspective view;
 FIG. 2 is a rear perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top view thereof; and,
 FIG. 8 is a bottom view thereof.

1 Claim, 6 Drawing Sheets(56)
